UNITED STATES PATENT OFFICE.

PAUL WITTECK, OF BUTLER, NEW JERSEY, ASSIGNOR TO THE BUTLER HARD RUBBER COMPANY, OF NEW YORK, N. Y.

DESIGN FOR A COMB.

SPECIFICATION forming part of Design No. 18,214, dated March 27, 1888.

Application filed July 30, 1887. Serial No. 245,756. Term of patent 3½ years.

To all whom it may concern:

Be it known that I, PAUL WITTECK, a citizen of the United States, residing at Butler, in the county of Morris and State of New Jersey, have invented and produced a new and original Design for Combs, of which the following is a specification.

My invention relates to a design for a comb, and has for its object to so decorate the back thereof as to present a pebbled surface.

Reference is to be had to the accompanying drawing, forming a part of this specification, in which the figure of the drawing illustrates a side elevation of my newly-designed comb.

The leading feature of my design consists of a series of closely-grouped protuberances, representing and imparting the effect of pebbled leather.

At the base of the back and above the teeth of the comb a band, A, is extended longitudi-

nally from end to end of the comb, and above the said band, on the surface of the back, a series of closely-grouped figures, a, are produced, representing protuberances and presenting to the eye the effect of a covering of pebbled leather. The contour of the back is concavo-convex, at the ends convex, and at the bottom straight.

I claim—

The herein shown and described design for a comb, consisting of a longitudinal plain band, A, above the teeth at the base of the back, and a series of closely-grouped protuberances, a, on the back and above the said band, as set forth.

PAUL WITTECK.
